UNITED STATES PATENT OFFICE.

STEPHEN P. M. TASKER, OF PHILADELPHIA, PENNSYLVANIA.

MACHINE FOR MAKING TUBES FROM HOLLOW INGOTS.

SPECIFICATION forming part of Letters Patent No. 331,572, dated December 1, 1885.

Application filed July 20, 1885. Serial No. 172,045. (No model.)

To all whom it may concern:

Be it known that I, STEPHEN P. M. TASKER, a citizen of the United States, residing in the city and county of Philadelphia, and State of Pennsylvania, have invented certain Improvements in Machines for Making Tubes from Hollow Metal Ingots, of which the following is a specification.

The object of my invention is the manufacture of a tube from a hollow cylindriform metal ingot by rolling, either hot or cold, by means of the machine hereinafter described, the said ingot down and out upon a mandrel at least of the required length of the tube to be formed, thereby compacting and consolidating the substance of the metal of the ingot, thinning or reducing the latter in thickness and elongating it until the required proportions are attained. The ingots which I employ are tubular or of a hollow cylindriform structure, of any metal, and either open at both ends, closed at one end, or closed at one end and provided through such closed end with an aperture for the traction-rod of a mandrel.

As my machine is of especial applicability to the making of steel tubes, I contemplate also the employment of a steel cast ingot of a character invented by me, two applications for patents for which were filed in the United States Patent Office upon the 14th day of May, 1885, and respectively numbered 165,695 and 165,696.

Heretofore in the art of metal-rolling, two or more pairs or sets of equal-sized concave-faced rolls, the two rolls constituting the respective sets or pairs of which, being placed the one over the other, have crossed each other—that is to say, have been adjusted in such manner that vertical planes, respectively projected from their respective longitudinal axes have intersected each other at other than a right angle—have been, in successive disposition in the same machine, employed for rounding, straightening, and sizing tubes and rods, the said tubes or rods having been passed through the passes of the successive sets in a direction which may, for the purposes of explanation, be described as right angular to a common imaginary longitudinal axis of each pair of rolls; or in a direction much more nearly right angular to than parallel with the longitudinal axis of each individual roll of each

pair. In such a machine all of the rolls upon a given side of the line of feed of the rod have, moreover, been arranged in a common frame 55 with their axes parallel, and all of the rolls upon the other side of said line of feed have likewise been arranged in another common frame with their axes parallel, but angularly disposed with respect to or “crossing,” 60 so to speak, the axes of the other series, the passes of all the sets having been of the same diameter, and a common simultaneous adjustment of all of the passes having been the only adjustment thereof possible. Heretofore, also, 65 in the art of metal-rolling, two or three equal-sized rolls having concave working faces have been arranged in a suitable housing obliquely side by side, or one over the other, or spirally, as it were, around a common central imaginary 70 longitudinal axis of the set, so that the axes of the respective rolls forming such set have been inclined to each other in different planes, and each and all at an angle to the said common longitudinal axis, which is that of the article 75 to be rolled, the said article having been introduced through a pass extending longitudinally between or “through,” so to speak, the rolls, (which pass, as is well known, is an extended straight bearing obtained between 80 the roll-faces in a line bisecting the angle of inclination of the rolls,) and the said machines, as such, having been employed for rolling, finishing, reducing, straightening, and smoothing rods, tubes, shafting, and other cylindric 85 or tubular articles, which receive a spiral or combined rotary and progressive movement from the rolls, which not only form the article to a true cylindrical shape, but at the same time feed it forward.

I am not aware that sets of rolls arranged in the foregoing manner have been arranged in series.

Assuming a set of rolls of the character last above described as a given type, I may assume 95 a set of rolls of the character first above described as another given type, and may define the distinguishing characteristic of the two types to be the direction in which the article to be rolled is passed through the set of rolls—100 that is to say, whether it be passed through them in a direction right angular to what we may term their “common axis,” as in the case of the rolls first described, or parallel or co-

incident with said common axis, as in the case of the rolls last above described.

I have discovered that a superior merchantable tube of metal, but especially that a steel tube, can be economically and successfully manufactured either from a tubular metal ingot, or especially from a hollow steel-casting ingot, by employing in conjunction with a series of sets of concave-faced rolls, the rolls of each of which sets cross each other, and the reducing passes of which sets are successively smaller, a mandrel adapted to be rotated with the ingot upon it, and at least of the required length of the tube to be formed from said ingot, which mandrel is passed through the passes of the sets in a direction right angular to their common axes, and upon which the substance of the metal of the ingot is by the rolls compacted and consolidated, and the ingot itself thinned or reduced in thickness and elongated until the required proportions are attained.

Apparatus embodying a good form of my invention is represented in the accompanying drawings and described in this specification, the particular subject-matter claimed as novel being hereinafter definitely specified.

In the accompanying drawings, Figure 1 is a top plan view of an apparatus conveniently embodying a good form of my improvements and containing a series of two sets of rolls, an ingot having a closed advance end being shown in position upon the mandrel and undergoing reduction in its passage through the rolls in the direction of the arrow upon it. Fig. 2 is a central vertical longitudinal sectional elevation of the apparatus, represented in Fig. 1, section being supposed in the plane of the dotted line xx of Fig. 1, and sight being taken in the direction of the arrows upon said line, the reduction of the ingot being also illustrated, and the latter being closed at one end and provided through its closed end with an aperture through which the traction-rod of the mandrel is represented as having been passed. In Fig. 1 it is to be assumed that the mandrel is, if it be desired to apply power to it, forced from behind through the rolls. In Fig. 2 it is to be assumed that the mandrel is, if desired, being both forced and drawn, or drawn only. Fig. 3 is an end elevational view of the apparatus of Fig. 1, sight being taken from the left-hand end of said Fig. 1, but such a mandrel and ingot as are represented in Fig. 2 being shown in the pass. Fig. 4 is a fragmentary side elevational detail of one of the cylindriform segments, c , of the housing C , it being that segment to which the arrow a on said Fig. 1 points. Fig. 5 is a face view of one of the rolls and of one of the adjustable boxings in which one of its axles is journaled, the said boxing and the radial adjusting-arm thereon and a portion of one of the cylindriform segments of a housing and of the projecting flange thereof being represented in a sectional view projected on a plane which passes through both the axis of the roll and that of the radial adjusting-arm. The view is

in the nature of an explanatory diagram, and is neither drawn to scale nor isometrically correct. Fig. 6 is a detail illustrating how the mandrel may be swiveled to a mandrel-head or cross-bar, S , of a mandrel frame or carriage.

Similar letters of reference indicate corresponding parts.

In the drawings, A represents any suitable bed or foundation for supporting the housings within which the rolls are journaled.

M is the advance portion of a cylindrical mandrel, which is at least of the length of the tube to be produced, and which is adapted to be rotated upon its longitudinal axis by any convenient means—as, for instance, by swiveling its rear extremity in the mandrel frame or carriage.

In the drawings no representation other than that of a mandrel-frame head in section is made of any means for occasioning the advance or retraction of the mandrel through the passes of the rolls, for the reason that I assume such representation to be unnecessary, because the various appliances in common use for actuating the mandrels of rolling-mills are well known to iron-masters, and for the further reason that any such means are of optional application, as the rolls are provided with means for driving them, and consequently for operating the mandrel when the ingot upon it is in bite with the rolls. I assume it, however, to be understood that a suitable mechanism, which may be of any preferred character, is, when it is desired so to do, to be applied to the mandrel to co-operate with the means for driving the rolls in causing the advance or retraction of the mandrel and ingot at any predetermined speed through the passes of the rolls.

B is an ingot upon the mandrel.

C are two longitudinally-extending parallel housings vertically erected from the bed or foundation, and either cast solid therewith or bolted or otherwise secured thereto. The housings in the form of apparatus shown in the drawings—and it is to be borne in mind that the series may contain a greater number of sets of rolls than two—support two successively-placed sets of rolls, the rolls of the first set of which are marked D , while the rolls of the second set are marked E . The two rolls of each set may be relatively of the same size; but the concave working-surfaces of the two rolls of the second set are to be more “filled in,” so to speak, than the working-surfaces of the rolls of the first set—that is to say, the diameter of the central portions of the rolls of the second set is to be greater than that of the rolls of the first set—so that the normal pass of the second set may be diametrically smaller than the normal pass of the first set, and this normal relation of successively-diminishing passes is to be preserved, whatever number of sets of rolls happen to be employed. The two rolls of each set are respectively adjusted one above the other, and their axes, whatever for

the time being be the adjustment of the rolls, must always cross at an angle other than a right angle, and which is such as to cause the concave working-surfaces of the said two rolls 5 to always present, in any desired angular relationship not right angular, a pass which, viewed from the end of the machine, is, as shown in Fig. 3, practically circular, whatever its diameter may be; for of course the 10 rolls separate and their pass increases diametrically as the angle of their axes increases. The journaling or housing of each set of the rolls and the means for adjusting the said two rolls of each set are preferably precisely 15 similar throughout any number of sets which may be employed. I will therefore describe the same with reference to but one set of rolls. Each housing in the region of its support of 20 a set of rolls has preferably the form of a segment of a vertical cylinder, the said cylindrical segments being marked $c c^x$ in the drawings, or, at least, the said housings are vertically cylindrically concaved on their adjacent faces, the curvature being the same in each, while 25 the inner faces of said cylindrical segments of the housings are separated from each other a distance equal to the diameter of a circle an arc of which corresponds with the arc of their inner curved cylindrical faces—that is to say, 30 a circle whose circumference is equal to that of the base of a supposed cylinder introduced vertically, so as to fill the space between the cylindrical segments of the housing. The curved inner walls of both the segmental portions 35 c and c^x therefore have a common central vertical axis which is midway between them. The axles d of the rolls are preferably entered within adjustable boxings or bearings $F F^x$, which are respectively fitted with 40 respect to, as shown in Fig. 5, and adapted to have both a rotary and a longitudinal movement within reversely-disposed segmental ways H , formed in opposite pairs in the respective cylindrical segments of the housings, 45 and two of which are as to each housing projected in what may be termed "diagonally-quartered relationship" upon a common radius from a common center, which is concentric with what I have characterized the "common longitudinal axis" of the rolls of the set 50 under consideration, and is about midway of the vertical depth of the said cylindrical segments, as will be more clearly understood by a reference to the drawings. By virtue of 55 these pairs of reversely-disposed segmental ways within which the axles of the rolls are, as shown, entered, the movement of the rolls of each pair for increasing or diminishing the diameter of their pass becomes both certain 60 and easy.

To render easy the adjustment of the rolls, I have devised the following convenient means of adjustment: A radially-projecting threaded adjusting-arm, f or f^x , is attached to each 65 axle-boxing, and passes through a doubly-curved slot, i , formed in a doubly-curved flange, I , projecting from the exterior face of

each cylindrical segment, as a reference to the drawings will also make clear. j are jam-nuts applied to the radial adjusting-arms to secure 70 the locking of the arm to which they are respectively applied at given positions with respect to its range of play within the slot of its flange. A suitable arrangement or disposition of the segmental ways for the axle-boxings with respect to the cylindriform segments of the housing is represented in the drawings, and will be easily understood by a reference thereto. The corresponding segmental ways in opposite cylindrical segments 80 are of course diagonally opposite. The segmental ways, axle-boxings adjustable therein, radial nut-provided arms connected with said boxings, and projecting slotted flanges for the maintaining of the arms when locked, 85 and consequently of the axles and rolls in predetermined positions, together constitute simply a composite roll-adjusting contrivance, the office of which is to permit of and render easy the adjustment of any given pair 90 (or of all the pairs) of rolls at different relative angles, and consequently, by reason of the play of their boxings in the reversely-disposed segmental ways, nearer together or farther apart, so as to increase or lessen the di- 95 ametric measurement of the pass between them and adapt them for employment with mandrels and ingots of varying diameters. Any other adjusting device operating to a similar result may, however, be substituted in 100 the stead of the foregoing. It is proper also to remark that the boxings may be dispensed with and the axles otherwise housed or entered simply in the segmental ways, in which event means for fixed adjustment of the rolls 105 is to be applied to the axles, and not to the boxings. As a gearing to occasion the positive driving in opposite directions of the two rolls of each set, I equip the said rolls with toothed 110 wheels $K K^x$, the teeth of which are of such form and spaced at such distances apart that, notwithstanding varying relative inclinations and consequent distances apart of the rolls, the said toothed wheels are in constant engagement, so that when rotation is imparted 115 to one of them rotation in a contrary direction is also imparted to the other; and I also provide driving spur-wheels $L L^x$ upon shafts $l l^x$, suitably journaled, preferably beneath the foundation of the machine, the teeth of 120 which respectively engage with the teeth of the lower toothed wheels, K^x , and occasion the rotation of the rolls to which they are applied in either direction at will. The housings constitute a most convenient framing; but the 125 segmental ways may be formed independently of or supported separately from the said housings.

Having now described what I believe to be a convenient embodiment of my invention, 130 and at the same time described the operation of the machine, it is proper for me to add that I believe myself to be the first to use a mandrel capable of rotation about its longitudinal

axis and of the length of the tube which is to be produced in conjunction with a series of sets of angularly-disposed or crossing concave-faced rolls having successively-diminishing passes, by which arrangement it is possible to reduce the external diameter of an ingot placed upon the mandrel, and, if desired, by setting down the rolls after each pass, to effect a continued reduction until said ingot becomes a tube of the desired thickness of substance and of no greater length than the mandrel. It is of course obvious that while the housing for containing and the means for retaining the adjusted rolls which I have represented and described are well adapted for the purpose, yet that they are not essential to my invention, the special adjusting devices described, or others operating to substantially the same result, however, permit of the adjustment of the rolls to accommodate any size of ingot within their range of separation. Whatever, moreover, may be the diameters of the passes of the rolls, all of the upper rolls throughout the series will be parallel with each other, and all the lower rolls in like manner parallel, and this notwithstanding the fact that the pass diminishes with each succeeding set. This capability of adjustment while the parallelism of the rolls is preserved is most important, as otherwise the rolls of the several sets would not act harmoniously, but would tend to roll the metal in different directions, owing to their irregularly-divergent angular positions; and it will therefore be understood why it is preferable to have all the rolls of each set of the same size, but to have the diameters of the concave working-faces of the rolls of different sets different. It is, however, proper to state that while I have herein recited as the best construction that the concave working-surfaces of the two rolls of the second set should be more filled in than the working-surfaces of the rolls of the first set—that is to say, should be of greater diameter at their central portions than the rolls of the first set, and so on throughout the series—yet that all of the rolls of all of the sets may, if desired, be of the same diameter, and the successively-diminishing diameters of the pairs be secured simply by the adjustment of each succeeding set. This construction would of course prevent the parallelism of all the upper rolls and all the lower rolls, and would not conduce to an equally successful manufacture. It would, however, be a possible construction, and is of a character clearly within my invention and contemplated by me. While it is preferable that the passes of the succeeding sets should successively diminish—that is to say, diminish in strict consecution, set by set, and without variance, omission, or alternation yet all the results which flow from consecutive diminution may be obtained by making, for instance, two consecutive or adjoining sets of a given and the same diameter of pass by making the two immediately-succeeding consecutive or adjoining sets of a lesser but of the same diameter of

pass, and by making the two further immediately succeeding consecutive or adjoining sets of a still lesser but of the same diameter of pass. This arrangement, or one kindred to it, the number or series of sets of similar diameter of pass employed not being vital, is not desirable; but it is manifestly embraced within my invention, and the terms "successive" or "gradual" diminution herein employed are not to be understood as employed with literal exactness.

The method of driving the rolls which I have represented is a good one, because it permits of their reversal for the backing out of the mandrel, and also the driving of different sets at different rates of speed. As already stated, the mandrel, which may be of any desired kind, may, when it is desired to apply power to it, be driven at a speed greater or less than that of the rolls, and is, when so driven, preferably driven by a power independent of the power employed to drive the rolls. It is of advantage to increase the speed of each subsequent set of rolls to a degree necessary to take up what would otherwise be the undue stretching of the material. The ingots may be rolled down either hot or cold. The spiral or revolving progressive motion to which the ingot on the mandrel, and with it the mandrel to which it for the time being adheres, is subjected prevents finning or irregularities of any kind, and therefore tends to produce a uniformly-cylindrical and very marketable tube. The mandrel may be extracted from the tube after rolling by stretching the tube, by loosening the mandrel, and by extracting the latter by any suitable means.

It is proper to add that my machine without the mandrel is well adapted for reducing the diameters of tubes or rods, and, if desired, by a suitable adjustment of its several passes for rounding, straightening, and finishing such products, it being simply necessary for any such employment of said machine that the mandrel should be removed and the product to be operated upon be manipulated in its stead through the passes between the rolls.

I do not claim or seek herein to cover in connection with sets of rolls of the character herein set forth, which are provided with positive mechanism for driving them, any mechanism for positively advancing or retracting the mandrel, as, while I may see fit to employ in connection with this apparatus means for operating the mandrel at either a greater or a lesser speed than that imparted to the rolls, and although I deem such proceeding clearly within my invention, yet I have made the driving of the mandrel the subject of claim in another application, which I have designated "Case A, No. 3," and executed and filed contemporaneously with this application. I do not, moreover, claim herein the mandrel, *per se*, when employed with a set of concave-faced cross-rolls, nor yet the housing provided with segmental ways, nor, again, the roll-adjusting devices, as these features con-

stitute the subject-matter of another application contemporaneously executed and filed, and designated by me "Case A, No. 1."

Having thus described my invention, I claim

5 and desire to secure by Letters Patent—

1. In a machine for making tubes from hollow metal ingots, the combination of a series of sets of concave-faced rolls, each of which sets consists of a pair of concave-faced rolls 10 arranged with their axes inclined to each other, and the passes of such sets gradually diminish in diameter, with a mandrel at least as long as the tube to be formed, and which is passed through the passes formed by 15 the rolls of the successive sets in a direction right angular to the common axis of each pair or set of rolls, and mechanism for driving the rolls, substantially as set forth.

2. In a machine for making tubes from hollow metal ingots, the combination of a series 20 of sets of concave-faced rolls, each of which sets consists of a pair of concave-faced rolls arranged with their axes inclined to each other, and the passes of such sets diminish gradually 25 in diameter, with a mandrel adapted to be rotated about its longitudinal axis, at least as long as the tube to be formed, and which is passed through the passes formed by the rolls of the successive sets in a direction right angular 30 to the common axis of each pair or set of the rolls, and with mechanism for driving the rolls, substantially as set forth.

3. In a machine for making tubes from hollow metal ingots, the combination of a series 35 of sets of concave-faced rolls, each of which sets consists of a pair of concave-faced rolls arranged with their axes inclined to each other, and the concave working-faces of the rolls of each succeeding set of such series are more 40 filled in and of greater diameter than the rolls of the set immediately preceding, so that the passes of the sets gradually diminish in diameter, with a mandrel at least as long as the tube to be formed, and which is passed through 45 the passes formed by the rolls of the successive sets in a direction right angular to the common axis of each pair or set of rolls, and with mechanism for driving the rolls, substantially as set forth.

50 4. In a machine for making tubes from hollow metal ingots, the combination of a series of sets of concave-faced rolls, each of which sets consists of a pair of concave-faced rolls arranged with their axes inclined to each other, 55 and the concave working-faces of the rolls of each succeeding set of such series are more filled in and of greater diameter than the rolls of the set immediately preceding, so that the passes of the sets gradually diminish in diameter, with a mandrel adapted to rotate about 60 its longitudinal axis, at least as long as the tube to be formed, and which is passed through the passes formed by the rolls of the successive

sets in a direction right angular to the common axis of each pair or set of rolls, and with 65 mechanism for driving the rolls, substantially as set forth.

5. In a machine for making tubes from hollow metal ingots, the combination of a series of sets of concave-faced rolls, each of which 70 sets consists of a pair of concave-faced rolls arranged with their axes inclined to each other, housings for supporting said sets of rolls, reversely-disposed segmental ways for the axles of each set of the rolls, the arrangement being 75 thereby such that each set of rolls is capable of an independent adjustment, a mandrel adapted to be rotated about its longitudinal axis, and which is passed through the pass of each set of rolls in a direction right angular to the 80 common axis of each set, and mechanism for driving the rolls, substantially as set forth.

6. In a machine for making tubes from hollow metal ingots, the combination of a series of sets of concave-faced rolls, each of which 85 sets consists of a pair of concave-faced rolls arranged with their axes inclined to each other, housings for supporting said sets of rolls, reversely-disposed segmental ways for the axles 90 of each set of the rolls, means for securing the fixed adjustment of the axles of the sets of rolls with respect to their segmental ways, the arrangement being thereby such that each set of rolls is capable of an independent adjustment, a mandrel adapted to be rotated 95 about its longitudinal axis, and which is passed through the pass of each set of rolls in a direction right angular to the common axis of each set, and mechanism for driving the rolls, substantially as set forth.

7. In a machine for making tubes from hollow metal ingots, the combination of a series of sets of concave-faced rolls, each of which sets consists of a pair of concave-faced rolls arranged with their axes inclined to each other, 100 housings for supporting said sets of rolls, reversely-disposed segmental ways formed in or connected with the framing, boxings or bearings for the axles of the rolls of each set adapted to said segmental ways, adjusting-arms connected with both the axles of the rolls of each set and with the framing, the arrangement being thereby such that each set of the rolls is capable of an independent adjustment, a mandrel adapted to be rotated about its longitudinal axis, and which is passed through the pass 105 of each set of rolls in a direction right angular to the common axis of each set, and mechanism for driving the rolls, substantially as set forth.

In testimony whereof I have hereunto signed my name this 6th day of July, A. D. 1885.

STEPHEN P. M. TASKER.

In presence of—

J. BONSALL-TAYLOR,
JOHN JOLLEY, Jr.
